UNITED STATES PATENT OFFICE.

WINFIELD DUBOIS, OF DETROIT, MICHIGAN.

BOAT-DAVIT GEAR.

1,191,163.

Specification of Letters Patent. Patented July 18, 1916.

Application filed October 28, 1915. Serial No. 58,322.

To all whom it may concern:

Be it known that I, WINFIELD DUBOIS, a citizen of the United States of America, residing at Detroit, in the county of Wayne 5 and State of Michigan, have invented certain new and useful Improvements in Boat-Davit Gear, of which the following is a specification, reference being had therein to the accompanying drawings.

10 Revised United States boat regulations require the installation of some means whereby life saving boat davits can be safely and expeditiously swung from an inactive position to an overhanging active position whereby a life saving boat can be quickly lowered. In order that such requirements can be fulfilled, I have devised a novel gear including positive and reliable means for swinging a davit, said gear being 15 of such construction as to remain in operative relation relative to the davit irrespective of stresses, strains and lateral movements of the davit.

20 My invention further aims to provide 25 davit turning mechanism wherein the parts are constructed with a view of reducing the cost of manufacture and at the same time retain the features by which safety, durability, simplicity and ease of assembling are 30 secured, and with such ends in view, my invention resides in the novel construction, combination and arrangement of parts to be hereinafter specifically described and then claimed.

35 Reference will now be had to the drawing, wherein—

Figure 1 is a sectional view of a portion of a boat deck showing an installation of my new davit gear; Fig. 2 is an enlarged 40 view of a pillar or stanchion, partly broken away and partly in section; Fig. 3 is an enlarged horizontal sectional view of the davit gear, partly in plan, Fig. 4 is a cross sectional view taken on or about the line 45 IV—IV of Fig. 3, and Fig. 5 is a sectional view illustrating a modification of my invention.

In the drawings, 1 denotes a davit or boat crane having the upper curved end thereof 50 provided with the usual block and tackle 2 whereby a boat 3 may be raised and lowered. As illustrated, the davit or boat crane is rotatable in an upper deck 4 or roof of another deck 5, which is provided with a bearing plate 6 for the lower end of the davit or boat crane.

The davit or boat crane may be of any cross sectional area and suitably mounted thereon, adjacent to the lower end of the davit is a two-part clamp 7 provided with 60 a peripheral rib 8. Bolted or otherwise connected to the peripheral rib 8 is the web 9 of a large gear 10, said gear having internal annular tracks 11. Mounted on the deck 5, contiguous to the lower end of the davit 1 65 is a pillar or stanchion 12 terminating in a ball member 13 having a transverse opening 14. Extending through the opening 14 is the stem 15 of a revoluble shaft 16 provided with socket members 17 and 18 engaging the ball member 13. The socket member 17 is shrunk or otherwise mounted upon the stem 15 and the socket member 18 is retained thereon by a washer 19 and a crank 20, the latter being fixed for rotative 70 continuity with the shaft 16. On the outer end of the shaft 16 is a worm 21 meshing with the gear 10, and this worm is within a sectional or twopart housing 22 loose upon the shaft 16. The housing 22 has parallel 75 side flanges 23 provided with bearing surfaces 24 for spindles 25 upon which revolve anti-frictional rollers 26 engaging the annular tracks 11 of the gear 10. The rollers 26 coöperate with the bearings 24 in supporting the housing 22 in proper relation to the gear 10, and as said housing is loose upon the shaft 16, said shaft is held with the worm normally in engagement with the gear, whereby movement imparted to the 80 shaft 16 by the crank 20 causes the gear 10 to be rotated and the davit or boat crane 85 swung from its normal inactive position to an overhanging active position, whereby a boat may be lowered or raised.

In some instances, as illustrated in Fig. 5, anti-frictional rollers 30 may be placed between the flanges 23 of the housing 22, at the sides of the rollers 26, to reduce wear 100 upon the sides of gear 10 and coöperate with the rollers 26 in holding the housing in proper relation to said gear.

Should there be any flexing action of the boat crane due to a load supported thereby, the ball and socket connection of the pillar 105 and the shaft 16 allow said shaft to adjust itself relative to the gear 10, and should there be a lateral tilting movement of said gear, then the bearings 24 allow the housing 22 to adjust itself relative to the gear, insomuch that the flanges 23 do not engage the gear, consequently there can be a lateral 110

tilting movement of the housing relative to the gear.

One embodiment of my invention has been illustrated but it is to be understood that the structural elements are susceptible to such variations and modifications as fall within the scope of the appended claims.

What I claim is:—

1. The combination with a boat davit, of a gear detachably connected thereto, a pillar adjacent said gear, a revolute shaft having a ball and socket connection with said pillar, a worm on said shaft meshing with said gear, and a housing movably engaging said gear and adapted to maintain said worm in engagement therewith.
2. The combination with a rotatable boat davit, of a gear detachably connected thereto, a pillar adjacent said gear, a revolute shaft supported by said pillar, a worm on said shaft meshing with said gear, a housing loose on said shaft and having bearings at the sides of said gear, means in connection with said bearings adapted to maintain said worm normally in engagement with said gear.
3. A turning mechanism for boat davits, comprising a gear adapted for attachment to a davit, a revolute shaft adapted to adjust itself relative to said gear, a worm on said shaft meshing with said gear, and means inclosing said worm and engaging

said gear adapted to maintain said worm normally in engagement with said gear.

4. A turning mechanism for boat davits comprising a gear adapted for attachment to a davit, said gear having internal annular tracks, a revolute shaft adjacent said gear, and adapted to adjust itself relative to said gear, a worm on said shaft meshing with said gear, a housing loose on said shaft inclosing said worm and having bearings at the sides of said gear, and revolute rollers carried by the bearings of said housing and engaging the annular tracks of said gear.

5. A davit turning mechanism comprising a gear adapted for attachment to a davit, said gear having annular tracks, a pillar adjacent said gear, a revolute shaft having a ball and socket connection with said pillar, a worm on said shaft meshing with said gear, a housing loose on said shaft inclosing said worm and having bearing surfaces at the sides of said gear, revolute rollers supported by the bearing surfaces of said housing and engaging the annular tracks of said gear, and means for imparting movement to said revolute shaft.

In testimony whereof I affix my signature in presence of two witnesses.

WINFIELD DUBOIS.
